UNITED STATES PATENT OFFICE.

LEWIS E. WATERMAN, OF ROCKFORD, ILLINOIS, ASSIGNOR TO EMERSON MANUFACTURING COMPANY, OF ROCKFORD, ILLINOIS, A CORPORATION OF ILLINOIS.

ALFALFA-DISK.

No. 903,119.

Specification of Letters Patent.

Patented Nov. 3, 1908.

Application filed April 21, 1908. Serial No. 428,451.

To all whom it may concern:

Be it known that I, LEWIS E. WATERMAN, a citizen of the United States, residing at Rockford, in the county of Winnebago and 5 State of Illinois, have invented certain new and useful Improvements in Alfalfa-Disks, of which the following is a specification.

The object of this invention is to construct an alfalfa disk to be used in the renovation of alfalfa, clover and like meadows, and so constructed that any one double tooth can be removed and another inserted without disturbing any of the others.

In the accompanying drawings. Figure 15 1 is an elevation of one face of the disk. Fig. 2 is an elevation through the disk on a line cutting through two oppositely disposed double teeth. Fig. 3 is an elevation of the face of the plate to which the teeth are 20 secured. Fig. 4 is a perspective view of a portion of the disk. Fig. 5 is a perspective view of a double tooth.

The plate 1 is circular in outline and has a central hub 2 provided with a square opening 3. One face of this plate 1 is formed with an edge flange 4 which has cut-away portions 5. Adjacent to each cut-away portion is located a V shaped projection 6, and near the apex of these projections is located 30 a curved projection 7. An opening 8 is formed through the projection 6 and through the plate which is formed integral therewith.

A plurality of double teeth are secured to the face of the plate from which the sectional flange 4 extends. Each double tooth is formed of a single piece having a head portion 9 from which extends the pointed prongs 10. The underface of the head portion 9 is formed with a recess 11 and an 40 opening 12 is formed through the head portion. The double teeth are all secured to

the plate 1 in the same manner. The recess 11 in the underface of the head portion is placed over a V shaped projection 6 and the end of the head portion 9 is located against 45 the curved projection 7. The other sides of the head portion rest in contact with the ends of the flange forming the cut away portions. A bolt 13 is passed through the hole 8 in the plate 1 and V shaped projection 6 and through the hole 12 in the head portion 9 of the double tooth, and receive a nut 14 on its projecting end. The heads of the bolts are counter-sunk in the plate 1. As each double tooth is secured to the plate independently of the others, any one can be removed and replaced by the new one without disturbing the others, or without destroying the plate in its connection with the other plates of a gang.

I claim as my invention.

1. A tooth for harrows, comprising a head and two pointed prongs, the underface of the head formed with a recess and an opening through the head.

2. A disk provided with a plurality of independently removable double teeth, each tooth comprising a head and two pointed prongs, the underface of the head formed with a recess which receives a projection extending from the head of the disk and an opening through the head, and a bolt passing through the opening and through an opening in the disk.

In testimony whereof I have hereunto set 75 my hand in presence of two subscribing witnesses.

LEWIS E. WATERMAN.
